[57] CLAIM

The ornamental design for a front face of a vehicle wheel, as shown and described.

DESCRIPTION

FIG. 1 is a front elevational view of the front face of a vehicle according to the invention; and

FIG. 2 is a perspective view of the front face of a vehicle wheel as shown in FIG. 1.

The broken line showing the rear portion of the vehicle wheel in FIG. 2 is for illustrative purposes and forms no part of the claimed design.
